UNITED STATES PATENT OFFICE.

HARRY A. BLACKWELL, OF ST. LOUIS, MISSOURI, AND RICHARD M. WATSON, OF DETROIT, MICHIGAN.

LEAF HOLDER FOR LOOSE-LEAF BINDERS.

Application filed January 31, 1923. Serial No. 616,069.

To all whom it may concern:

Be it known that we, HARRY A. BLACKWELL and RICHARD M. WATSON, citizens of the United States, residing in the city of St. Louis and State of Missouri, and in the city of Detroit, county of Wayne, and State of Michigan, respectively, have invented new and useful Improvements in Leaf Holders for Loose-Leaf Binders, of which the following is a specification.

This invention relates to leaf holders for loose leaf binders of the type shown in the prior patent to R. M. Watson, No. 1,042,626, and has for its general object an improvement in the relative location of the parts and in their construction and mode of operation, whereby to increase the attractiveness and utility of the device and decrease the cost of production.

With these ends in view, the invention resides in the provision of a unitary clasping device mounted for insertion on and removal from a binder plate; in adapting the clasping device for location upon and operation over the flat side of the binder plate instead of mounting it on the channelled side, as heretofore; and, finally, in constructing the binder plate to have its channelled side secured to the back of the folder.

In the accompanying drawing—

Figure 1 is a view partly in plan and partly in section, illustrating a binder plate having a plurality of clasping devices mounted thereon, the sheath of one of said devices shown in section, and the binder plate being shown secured to the back of a folder, which is illustrated broken away;

Figure 2 is an end elevation with the clasping rings closed; and

Figure 3 is a similar view with the clasping rings open.

Referring now to the drawing, the numeral 1 indicates a binder plate which may be made of any desired length, and which has its side edges turned downward and inward at an angle to provide guides, or flanges, 2 for engagement by clasping devices to be mounted on the binder plate. At either end, the binder plate is provided with an aperture 3, the material of the binder plate surrounding which is pressed downward to form an abutment 4 lying flush with the edges of the flanges 2, which enable the central portion 5 of the binder, or folder, 6 to be secured by riveting, or the like, to the

abutments 4, which thus serve as supports for the back 5.

According to this invention, a plurality, for example three, clasping devices are designed to be slidably mounted on the binder plate 1, and the construction and manner of mounting one of the clasping devices on the binder plate will now be described.

The numeral 7 indicates a sheath of approximately the length shown in the drawings and having its side edges turned downward and shaped to provide grooved flanges 8, which are adapted to embrace the flange guides 2 on either side of the binder plate 1. The groove in each flange 8 is shaped to provide a shoulder 9, which rides upon the top of the binder plate, as more clearly shown in Figures 2 and 3, and furnishes a fixed sliding engagement of the clasping device with the binder plate. Mounted in each of the sheaths 7 are half-rings 10 and 11, which project upward from integral base members 12 and 13 through apertures 14 provided near one end of each of the sheaths 7. Each of the base members 12, 13 is in the form of a bent spring leg, as more clearly shown in Figure 1, the bent portions meeting at the center to form a toggle, as indicated at 15. The meeting surfaces of the toggle members may be held in fixed relation to each other by a tongue and groove connection, as indicated at 16. The sides of the spring legs bear against the sides of the sheath 7, and are thereby held under stress, this stress being sufficient to keep the half-rings in either open or closed position, according as the toggle members 15 are moved to position above or below the horizontal plane. This movement is effected by separating or bringing together the two half-rings 10 and 11, and in this movement, the spring members, or legs, 12 and 13 will be extended or will retract in a longitudinal direction, as will be understood.

By reference to the patent above referred to, it will be seen that the clasping devices are arranged to span the channelled side of the binder plate, and that the legs, or spring members, of the half-rings are mounted in the channel of the binder plate itself and slide therein, the sheath of each clasping device having its side edges bent to engage over the channelled sides of the binder plate.

When secured to the inside of the back of the binder, or folder, the channelled side

of the binder plate would lie upward, and such an arrangement gives a somewhat unfinished appearance to the binder as a whole.

It will be seen that by our arrangement the flat side of the binder plate is uppermost, and therefore presents a finished and more attractive appearance. It will further be seen that in the present arrangement, each clasp device is a unit, that is to say, it carries its own half-rings, which latter have their base members mounted between the flanged sides of the sheath 7 of the clasp device, instead of having them mounted between the flanged sides of the binder plate, as in the patent. This construction enables the clasp devices to be readily moved to any adjusted positions on the binder plate, as will be understood.

It will be understood, of course, that in common with the construction shown in the patent referred to, the clasp devices of the present invention have the half-rings located at one end of the sheath, and the clasp device as a whole may not only be mounted in various adjusted positions on the binder plate, but the relative distance between the half-rings of each clasp device may be further varied by reversing the positions of the sheaths on the binder plate.

30 We claim:

1. A leaf holder for loose leaf binders, having, in combination, a binder plate bent downward at its side edges to form guides, and a plurality of clasp devices slidably mounted on the binder plate and spanning the plain side thereof.

2. A leaf holder for loose leaf binders, having, in combination, a binder plate provided with terminal apertures having the 40 surrounding material extended outward to form abutments and provided with lateral

flanged guides on its side provided with said abutments, and a plurality of clasp devices slidably mounted on said binder plate to span the plain side thereof and having lateral grooves engaging said guides. 45

3. A leaf holder for loose leaf binders, having, in combination, a binder plate bent downward at its side to form guides, and a plurality of clasp devices slidably mounted on said binder plate, each of which comprises a sheath provided with lateral grooves to embrace said guides and a pair of half-rings having spring toggle members located within the sheath above the plain side of 55 said binder plate.

4. In combination with a folder, a binder plate having flanged guides at its sides and secured in said folder with its channelled side downward, and a plurality of clasp devices 60 slidably mounted on said binder plate, each of which comprises a sheath spanning the upper, or plain, side of said binder plate and provided with lateral grooves for embracing said guides, and spring toggle members located in the 65 grooves of said sheath and each of which has a half-ring projecting upward through an aperture near one end of said sheath.

5. A leaf holder for loose leaf binders, 70 having, in combination, a binder plate provided at its side edges with guides and presenting a continuous surface on its upper side, and a plurality of clasp devices 75 slidably mounted on the binder plate in engagement with said guides and spanning the upper side thereof.

In testimony whereof, we have hereunto set our hands.

HARRY A. BLACKWELL.
RICHARD M. WATSON.
